INVENTOR

UNITED STATES PATENT OFFICE.

APOSTOLOS C. ITHOMITIS, OF RAYMOND, WASHINGTON.

AUTOMATIC PISTOL.

Application filed March 27, 1922. Serial No. 547,219.

To all whom it may concern:

Be it known that I, APOSTOLOS CHRISTOPHILOS ITHOMITIS, a citizen of Greece, but who have declared by intention to become a citizen of the United States, and resident of the city of Raymond, in the county of Pacific and State of Washington, have invented new and useful Improvements in Automatic Pistols, of which the following is

10 a specification.

My invention relates to improvements in automatic firearms, and the objects of my invention are to provide means whereby the recoil of the explosion shall furnish energy 15 for ejecting the empty cartridge, reloading, and firing the new shot. Special objects of my invention are to provide an improved trigger mechanism and an improved magazine for cartridges.

20 I attain these objects by the mechanism illustrated in the accompanying drawings, in which—

Figure I is a vertical section of the pistol; Fig. II, an elevation with the front half 25 of the casing removed to show the cartridge magazine in place; Fig. III, a plan view showing the recoil chamber; Fig. IV, a sectional view of the magazine; Figs. V, VI and VII, are enlarged views of the trigger mechanism; Fig. VIII, a side view of the entire 30 pistol; Fig. IX, a horizontal section, showing manner of ejecting a cartridge; Fig. X, a cross section on line A—A; Fig. XI, and Fig. XII, are cross sections on lines B—B 35 and C—C; Fig. XIII, a rear view of the bolt; Fig. XIV, a horizontal sectional view of the bolt; Fig. XV, a vertical sectional view 40 through the magazine and pistol; Fig. XVI, a front end view of the bolt; and Fig. XVII, a side elevation of the bolt.

The numeral 1 designates the stock of the pistol, 2 the barrel, and 3 a cartridge within. Within the casing 5, is a chamber 6 for the trigger mechanism, and a chamber 7 for the 45 cartridge magazine. To the rear of the barrel 2 and in axial alignment therewith is a breech-chamber 8, and lying parallel thereto a recoil chamber 10. In the breech-chamber 8 is a bolt 12 designed to reciprocate therein, and provided with an arm 34 extending through a slot into the recoil chamber 10. A compression coil-spring 35 is mounted between studs in this chamber and serves to absorb the recoil of the explo-

sions upon said bolt and to cause the latter 55 to rebound to fire the next successive charge.

An arm 30 extends horizontally through a slot 43 in the side wall of the pistol-breech through which the bolt may be manipulated 60 by hand. Said bolt is formed with an interior chamber 21^a to receive a firing pin 11. A coil spring 14 lies within this chamber in such a way as to urge the pin forwardly. The front end of the firing pin protrudes 65 through the walls of chamber 21^a so as to strike the fulminating cap of the cartridge 3.

A trigger 19 is pivoted within the chamber 6 and connected to said trigger is a finger with segments 16 and 17. A coil spring 20 70 tends to pull this finger forward in an upright position, and a flat spring 18 tends to hold the uppermost segment 16 in alignment. Upon a projection of segment 17 rests one end of the lever 15. The other upturned 75 portion of the lever projects into the breech-chamber 8 and engages the head of the firing pin 13 upon its rebound. The segment 16 also projects in the path of the head of the firing pin.

The pistol is provided with a detachable magazine 33 for cartridges. Within this magazine is a flat folded spring 23 supporting a pan 41 upon which in superimposed order lie the cartridges 21 and 22. The 80 pan 41 is provided with an arm 31 which extends horizontally through a slot 32 in the wall of the magazine 25 by means of which the pan may be depressed for filling the magazine. The magazine may be removed or inserted by means of a hinged plate 46 at the bottom of the casing 29.

An extractor 42 pivotally connected to the bolt 12 is so arranged as slightly to project and seize the rim of the cartridge and withdraw it until the opposite edge of the rim strikes upon the pin 47. At the impact the cartridge is thrown out through opening 48 as shown in Fig. IX. A slot 49 in bolt 12 accommodates the passage of the bolt by 100 said pin.

The operation of the gun is as follows:

A cartridge being in position, as shown in Fig. I, the bolt is "cocked" by pulling back the bolt by means of arm 30 until the lug 13 105 is engaged by the dog 15. As said arm is released the power of spring 35 forces the bolt forward in the breech-chamber, but the firing pin is retained by the dog 15, and in

this manner the spring 14 compressed. Pulling the trigger releases the lug 13, upon which the spring 14 drives the firing-pin against the cap of the cartridge and explodes it.

The recoil of said discharge reacts upon the bolt 12, forcing it back against the compression of 35 until the force of the recoil is absorbed. Then the spring 35 reacts, drives the bolt forward again into position to fire the succeeding shot.

Pulling the trigger 19 raises the rear end of the lever 15 and lowers the forward end until the lug 13 is disengaged and the firing pin released. Upon the recoil of the bolt after the shot, the lug 13 pushes back the finger 16-17 thereby releasing the lever 15 from the notch in the finger-segment 17. Said lever is then forced upward by its spring 50 so as to engage the head of the firing pin 13 as before. With its backward motion the lug 13 releases the lever by pushing back the finger 16, but upon the forward motion spring 18 allows the tip 16 to bend forward until the lug has passed by. The next shot is fired by releasing the finger-trigger 19, and so allowing the segment 17 to drop down until its notch reengages the lever 15, whereupon pulling the trigger again fires the pistol.

As one cartridge is ejected the spring 23 forces up another into its place, and the bolt forces it forward into the shell chamber.

The automatic pistol is simple of construction, accessible to inspection and repair, and automatic in action, yet at all times under trigger control. A plate of metal 28 covers the rear portion of slot 40 and serves to make the weapon dust proof.

In my application No. 519,830, filed Dec. 5th 1921, I have shown a firearm with some of the same features appearing in the automatic pistol.

I claim:

1. In an automatic firearm, a trigger, two sections pivotally connected therewith, a spring tending to keep said sections in an upright position a flat spring tending to keep the second section in alignment with the first, and a sear controlled by said trigger and sections.

2. An automatic pistol including a barrel, a breech-chamber in axial alignment therewith and a recoil chamber parallel with said breech-chamber, a chambered bolt formed with an arm extending in said recoil chamber, a compression-spring in said recoil chamber arranged to exert its force upon said bolt through said named arm, a firing pin mounted in the chambered portion of said bolt and provided with a lug at its rear end exteriorly of the bolt, a coil spring tending to urge said pin forwardly, a trigger having an upturned finger yieldingly connected thereto, said finger composed of two sections, a spring drawing the finger forward, a second spring holding the top section in alignment with the lower section, and a sear controlled by said finger, an extractor on said bolt, a pin in the path of the shell being ejected, and upon the side opposite the extractor to act as stop and a fulcrum to eject the shell, a magazine having an opening in the side and detachable from said pistol, means for retaining said magazine within the pistol, a flat bent spring retained in said magazine, a plate above said spring, an arm affixed to said plate and extending through said opening.

In testimony whereof I affix my signature in the presence of two witnesses.

A. C. ITHOMITIS.
